UNITED STATES PATENT OFFICE.

JOHN PARTINGTON, OF SALTAIRE, ENGLAND.

RESILIENT-TIRED WHEEL.

SPECIFICATION forming part of Letters Patent No. 792,921, dated June 20, 1905.

Application filed January 10, 1905. Serial No. 240,416.

To all whom it may concern:

Be it known that I, JOHN PARTINGTON, a subject of the King of Great Britain and Ireland, and a resident of Dallam House, Saltaire, in the county of York, England, have invented 5 certain Improvements in and Relating to Resilient-Tired Wheels, (for which I have made application for a patent in Great Britain, No. 26,400, dated December 5, 1904,) of which the following is a specification.

This invention relates to certain improvements in connection with wheels suitable for motor-cars and like vehicles; and the object is to construct such wheels in a manner intended to remove the possibility of danger of 15 damage by puncture, surface cutting, or bursting of the pneumatic tube, also to prevent all creeping of the tube around the wheel circumference, and thereby reduce the wear and 20 tear, and to combine with the wheel-rim renewable tread-blocks so arranged that they are applicable for use in connection with pneumatic tubes for obtaining resilience, the tread-blocks being so constructed and applied that 25 side slipping or skidding is obviated and slipping prevented when hill-climbing.

In describing my invention in detail reference is made to the accompanying sheets of drawings, in which—

30 Figure 1 represents an elevation of a portion of a motor-car or like wheel arranged in accordance with my invention, part of the wheel-disk being removed for more clearly showing the tread-blocks. Fig. 2 is a section 35 through wheel-rim, showing ferrule and distance-piece in section. Fig. 3 is a similar section showing the invention applied to a wheel of ordinary construction having felloes and spokes. Fig. 4 is a section showing a composite 40 tread-block. Fig. 5 is a view showing supplementary provision for keeping grit and the like from base of tread-blocks and pneumatic tube. Fig. 6 is a side elevation of a portion of a wheel with front disk removed 45 for more clearly showing tread-blocks provided with protecting side plates. Fig. 7 is an end view of block; and Fig. 8, a side view of composite tread-blocks, such as shown by Fig. 4, with pieces of flexible tread inserted. 50 The wheel may be formed of two metal

disks 1, attached to a hub in a convenient manner and of a configuration at the rim for the reception, retention, and protection of a pneumatic tube 2, a ring of wood or other material 3 being placed between the disks to 55 form the bottom of cavity and to support the pneumatic tube 2 placed therein. Cavities 4 of convenient length and depth are cut at certain distances apart in ring 3, and into each cavity 4 a corresponding stop-piece 5 engages. 60 Such stop-pieces project from and form part of the pneumatic cushion-tube 2, which by engaging with the cavities positively keep the tube 2 in its relative position with regard to ring 3, by which creeping of tube 2 around 65 said ring is prevented.

The disks 1 are bent over at the circumference 6, and from this point they extend backward toward the wheel-axle, and the edge of each disk forms a flange or shoulder 7 70 within the cavity between the disks some distance from the circumference of same. The internal diameters of these flanges are the same. The sides of the disks within the annular space of said cavity between flanges 7 75 and the circumference 6 are flat and the space parallel, and into this parallel space are placed renewable tread-blocks 8, composed entirely of india-rubber or like flexible material, or partly so, as hereinafter described. Each 80 tread-block, whether composed entirely or partly of flexible material, has side projections 9 at base, adapted to engage with the before-mentioned flanges and also project into recesses at base of filled-in spaces 10, one on 85 each side, as shown.

The tread-blocks 8 when placed in position between disks 1 are there retained by the side projections 9, and at each end of tread-blocks a recess 11 is formed of such shape that when 90 two blocks come together the recesses form an oblong opening 11^A (see Fig. 1) for the reception of a metallic ferrule 12 of like shape, adapted to fill same and slide over a distance-piece 13, secured between the disks by a bolt 14, screwed 95 tight for keeping the disks rigid and before-mentioned annular space between same parallel, and by the ferrules being formed oblong and of a length to fill the annular parallel space between the disks sufficiently tight, but 100

free to slide therein, they assist in supporting and keeping the tread-blocks 8 in position when traveling, but allow them to yield radially under pressure.

5 The sides of each tread-block 8, of india-rubber or the like, in contact with the turned-over disks in annular parallel space may be faced with hard wearing material, such as metal plates 8^A, extending the length of each 10 block and of suitable depth and shape at 8^B to extend into recesses 11 at each end of block 8. The extensions 8^B meeting in the center act as a ferrule and protect the india-rubber the same as is the case when ferrules 12 are applied.

15 The base of tread-blocks under openings 11^A are in contact with each other—that is to say, they are end to end; but outside the ferrules or the like extending to the circumference of blocks an open space 15 is left.

20 The tread-blocks may be formed with a metallic base 8^C, such as shown by Figs. 4 and 8, and applied to the wheel-rim in the same manner as before described. These are faced at tread with flexible material 8^D, secured to

25 the metallic portion in a convenient manner, such as shown by Fig. 4. A flange 16 is formed at one end of metallic base for keeping the flexible tread in position, the latter being of such length as to leave an open space 30 between similar to 15 before described.

When pressure comes upon the blocks constructed and applied in the manner described, the ferrules 12 or the like, along with the affected blocks, slide in a radial direction, resilience being given by the pneumatic cushion-tube 2, and when pressure is removed the blocks are forced back until the side projections 9 engage with the flanges 7 and inserted packing within filled-in spaces 10, and by leaving an open space 15 between the blocks a better grip, and thereby less slipping on the ground, is obtained than is the case with wheels having a continuous tread-surface similar to a solid tire.

45 By forming the tread with sectional blocks and leaving open spaces 15, as described, side slipping or skidding when turning to the right or left is prevented, and by the engagement of stop-pieces 5 with cavities 4 creeping of 50 the pneumatic tube 2 around wheel is obviated.

By combining tread-blocks and disks as described and inserting a channeled flexible cover 17, as shown, between blocks and pneumatic tube grit, mud, and water are to a great extent, if not entirely, prevented getting into the interior in contact with tube 2; but as a

further precaution for keeping the surfaces between the sides of blocks 8 or plates 8^A and insides of disks free of dust and the like an 60 additional plate 18 may be inserted on each side, as shown by Fig. 5, and held in the required position by the distance-pieces 13 and bolts. The exposed portions of plates are bent at 18^A for the reception of and holding 65 in position an india-rubber or like flexible packing-cord 19, against the side of tread-blocks, thus assisting to keep away from the interior, moisture, grit, and other foreign matter.

70 What I claim as my invention is—

1. In a pneumatic-tired wheel, the combination with opposing disks 1 on the periphery of the wheel, said disks having their outer edges bent inwardly and backwardly so as to 75 form internal flanges 7, a pneumatic tire held between said disks, a channeled flexible cover 17 resting on said tire and sectional tread-blocks having radial projections 9, said blocks resting on the channel-cover with their projections engaging the flanges 7.

2. In a pneumatic-tired wheel, the combination with opposing disks 1, said disks having their outer edges bent inwardly and backwardly so as to form internal flanges 7, distance-pieces between the disks, means for holding said pieces in place sectional tread-blocks held movably in between the disks by 80 said distance-pieces, and projections on the lower part of said blocks engaging with the flanges 7, substantially as described.

3. In a pneumatic-tired wheel, the combination with opposing disks 1, sectional tread-blocks located between said disks each of said blocks having an oblong recess on each end 95 thereof which forms with the adjacent block an oblong opening and means secured to the disks passing through said opening so as to movably hold the blocks in place, substantially as described.

4. In a pneumatic-tired wheel, the combination with the disks 1 secured to the wheel, sectional tread-blocks located between the disks, means for holding said blocks movably in place, packing-cords 19 located at the outer junction of the blocks and disks and means for holding the cords in place.

In witness whereof I have hereunto set my hand in the presence of two witnesses.

JOHN PARTINGTON.
